US00D559826S

(12) **United States Design Patent** (10) **Patent No.:** **US D559,826 S**
(45) **Date of Patent:** **** Jan. 15, 2008**

(54) **MOBILE PHONE**

(75) Inventor: **Young-Keun Lee**, Seoul (KR)

(73) Assignee: **Samsung Electronics Co., Ltd.**,
Suwon-Si (KR)

(**) Term: **14 Years**

(21) Appl. No.: **29/266,318**

(22) Filed: **Sep. 19, 2006**

(30) **Foreign Application Priority Data**

Jul. 31, 2006 (KR) 30-2006-0032023

(51) **LOC (8) Cl.** **14-03**

(52) **U.S. Cl.** **D14/138**

(58) **Field of Classification Search** D14/137,
D14/138, 147, 218, 341-347, 496; 455/90.3,
455/556.1, 556.2, 575.1, 575.3, 575.4; 379/433.01-433.13;
361/814; 348/14.02

See application file for complete search history.
